UNITED STATES PATENT OFFICE.

JAMES V. WASHBURN, OF WATERBURY, CONNECTICUT.

DESIGN FOR A SAFETY-PIN.

SPECIFICATION forming part of Design No. 34,892, dated August 6, 1901.

Application filed May 6, 1901. Serial No. 59,055. Term of patent 14 years.

To all whom it may concern:

Be it known that I, JAMES V. WASHBURN, a citizen of the United States, residing at Waterbury, in the county of New Haven and State of Connecticut, have invented and produced a new and original Design for a Safety-Pin, of which the following is a specification, reference being had to the accompanying drawing, forming part thereof.

10 In the drawing I have represented my new design for a safety-pin by an elevation.

The leading or essential feature of my design consists in the ornamental shape and configuration of the bar *a*, which at the central portion is bent and in outline represents, substantially, the letter **M**.

15 The design of the safety-pin comprises, with the shield *b* at one end, the eye-bend *c* at the other end thereof, and the pointed pin-bar *d*,

the downwardly-curved quarter-circle bends 20 2 3, closely adjacent to the eye-bend *c* and shield *b* and forming part of the bar *a*, and the upwardly and downwardly extending parts 4 therefrom and intermediate thereto and also forming parts of the ornamental bar *a* and 25 in outline representing, substantially, the letter **M**, the ends of which terminate at the curved parts 2 3.

What I claim as new is—

The design for a safety-pin as herein shown 30 and described.

In testimony whereof I have signed my name to this specification in the presence of two subscribing witnesses.

JAMES V. WASHBURN.
